UNITED STATES PATENT OFFICE.

THOMAS H. RODMAN, OF NEW YORK, N. Y., ASSIGNOR TO THE CUTLER-HAMMER MFG. CO., OF MILWAUKEE, WISCONSIN, A CORPORATION OF WISCONSIN.

MOTOR CONTROLLER.

1,422,134.

Specification of Letters Patent. Patented July 11, 1922.

Application filed August 27, 1920. Serial No. 406,505.

To all whom it may concern:

Be it known that I, THOMAS H. RODMAN, a citizen of the United States, residing at New York, in the county of New York and State of New York, have invented new and useful Improvements in Motor Controllers, of which the following is a full, clear, concise, and exact description, reference being had to the accompanying drawing, forming 10 a part of this specification.

This invention relates to motor controllers and while not limited thereto is particularly applicable to controllers for printing presses.

Heretofore it has been customary to provide each control station of a printing press with a so-called "safe" switch adapted to be set manually to render all control stations ineffective for starting pending subsequent 20 operation of the switch so set. However, the protection afforded by such switches is rendered uncertain by reason of the fact that it is dependent upon an additional manual operation and hence dependent upon the 25 thoughtfulness of the operatives whereas failure to guard against accidental starting or starting without due notice often leads to serious consequences.

The present invention has among its objects to provide a controller having safety means which will greatly minimize the danger to which the attendants of the press or other controlled machine are subjected.

Another object is to provide safety means 35 capable of use in conjunction with safety means of the aforesaid character now in use.

Another object is to provide such additional safety means which may be readily embodied in various existing types of controllers.

Another object is to provide such additional safety means applicable to controllers for a single motor drive, a double motor drive or a plurality of drives of either type.

Various other objects and advantages of the invention will hereinafter appear.

The accompanying drawing illustrates a controller embodying the invention in one form and the same will now be described, it 50 being understood that the controller illustrated is susceptible of various modifica-

tions without departing from the scope of the appended claims.

In the drawing, Fig. 1 is a diagrammatic view of the controller;

Fig. 2 is a so-called "across the line" diagram illustrating the preferred motor connections; and

Figs. 3 to 5 are similar diagrams illustrating certain of the circuit connections of Fig. 1 in a manner to facilitate an understanding thereof.

Referring to Fig. 1 the controller illustrated therein is designed for a double motor drive shown in Fig. 2 as comprising a small motor M and a large motor M'. This controller comprises an electro responsive main switch 1 for the small motor, an electro responsive main switch 2 and dynamic brake 70 switch 3 for the large motor and a cross-head type rheostat R driven by a pilot motor M² to control said switches and to further control an armature resistance r and a field resistance r' for the large motor M', the resistance r being omitted from Fig. 1 but its contacts being illustrated therein and designated by the same reference character. An "on" relay 4 is provided to effect operation of the pilot motor for starting the motors 80 M and M' successively and for accelerating the latter while an "off" relay 5 is provided to effect reverse operation of the pilot motor. Also the controller includes a "stop" relay 6 to stop both motors, an "inch" relay 7 to start 85 and stop the small motor M, a "safe" relay 8 to render all of the aforesaid relays inoperative, a "paper-break" relay 9, and signal relays 10 and 11, all of said relays being under the control of a push-button station comprising an "on" switch 12, a "stop" switch 13, an "off" switch 14, a "safe" switch 15, an "inch" switch 16, and a "reset" switch 17.

While Fig. 1 shows but a single control station a plurality thereof may be provided as will hereinafter appear.

The switches 1 and 2 are preferably employed to establish the motor connections shown in Fig. 2, each of said switches being of the double pole type and having down contacts coacting to establish a dynamic braking circuit for its respective mo-

tor. Each motor is shown as comprising an armature a , a series field f and a shunt field f' , the motor M' having in circuit therewith the armature resistance r and field resistance r' to be controlled by the motor-driven crosshead. Also the motors M and M' are shown as respectively provided with resistances r^2 and r^3 in the dynamic braking circuits thereof, the motor M' having included in the dynamic braking circuit switch 3 which is of the normally closed type.

The "on" and "off" relays respectively establish the circuit connections for the pilot motor shown in Fig. 3, the pilot motor being shown therein as comprising an armature a and a series field f . Referring to this figure, it will be observed that the "on" relay which is of the double-pole type establishes connections whereby current flows through the armature and field in reverse directions whereas the "off" relay, which is of a similar type establishes connections for a unidirectional flow of current through both the armature and field.

The rheostat R has a main crosshead 18 and an auxiliary crosshead 19 the former coacting with contacts to control resistance r and r' and the latter coacting with the auxiliary contacts to control the windings of switches 1 to 3 as best illustrated in Fig. 4. This figure shows such auxiliary contacts and as will be observed the auxiliary crosshead 19 in its extreme position serves to connect contacts 20, 21 and 22 for connection of both the small motor switch 1 and large motor dynamic brake switch 3 across the line through the "inch" relay 7, "paper-brake" relay 9 and "stop" relay 6, relay 7 being normally open and relays 9 and 6 being normally closed. Thus in this position of the crosshead the small motor may be operated for inching by energizing relay 7. On the other hand when the rheostat is operated crosshead 19 leaves contacts 20, 21 and 22 interrupting the circuit through the "inch" relay and inserting interlocking resistances r^4 and r^5 in circuit with the windings of switches 1 and 3 respectively to necessitate return of the crosshead to initial position for re-energization of said switches following de-energization thereof. Upon initial movement of the crosshead 19 the same engages and bridges contacts 23, 24 and 25 which, assuming previous energization of switch 1 and 3, provides maintaining circuits therefor through auxiliary contacts 1* of switch 1 (Fig. 1). As will hereinafter appear, the "inch" relay is energized by closure of the "on" relay and thus both switches 1 and 3 are energized when the crosshead 19 is first moved and the former switch is maintained energized until said crosshead engages contact 23. Prior thereto the crosshead 19 engages contact 26 to complete the circuit of the large motor switch through the auxiliary contacts 1* of switch 1 and before disengaging contact 23 the crosshead engages contact 27 to parallel said auxiliary contacts by auxiliary contacts 2* of switch 2 (Fig. 1). Thus the auxiliary crosshead provides for starting the motors successively and de-energizing the main switch of the small motor after starting the large motor while maintaining the large motor switches 2 and 3 energized throughout the remainder of its movement, subject of course to de-energization by either the "stop" relay or "paper-brake" relay. As will be understood the auxiliary crosshead remains in engagement with contacts 24, 26 and 27 during movement of the main crosshead to vary the armature and field resistances of the large motor.

The push button station of Fig. 1 serves to establish the circuit connections shown in Fig. 5, the latter showing duplicate control stations. Referring to Fig. 5 the "on" switches 12 are connected in parallel and each serves to connect the winding of the "on" relay 4 across the line through the normally closed "safe" relay 8 and down limit switch 28 of the rheostat (Fig. 1). Thus the "on" relay 4 is rendered responsive to either "on" switch to complete the pilot motor connections as described while its auxiliary contacts 4* (Fig. 1) parallel the "inch" switches 16 (Fig. 5) to energize the "inch" relay for starting of the small motor and energization of the dynamic brake switch 3 of the large motor as above set forth.

The "off" switches 14 are also connected in parallel and each serves to connect the winding of the "off" relay 5 across the line through the safe relay 8 and up limit switch 29 of the rheostat (Fig. 1). Thus the off relay is responsive to either "off" switch to complete the pilot motor connections as above described for slow down.

The "inch" switches 16 have down contacts connected in parallel and either is adapted to be depressed to connect the winding of the "inch" relay 7 across the line through "safe" relay 8 whereby the "inch" relay is rendered responsive to start the small motor as above described. Also the "inch" switches 16 have up contacts connected in series and said switches normally connect the winding of the "paper-break" relay 9 across the line through parallel "paper-break" switches 30 each of which is adapted to be normally held open by the paper passing through the press subject to release upon breakage of the paper. Thus with the "inch" switches 16 in normal position release of either "paper-break" switch 30 energizes "paper-break" relay 9 to stop the motors as above described. On the other

hand depression of either of the switches 16 for inching interrupts the circuit of the "paper-break" relay thus permitting the press to be inched for rethreading or to be operated at a higher speed if desired by operation of one of the "on" switches 12 in addition to the "inch" switch 16.

The "safe" switches 15 as shown in Fig. 5 are connected in parallel and either is adapted to be set to connect the winding of "safe" relay 8 directly across the line for energization of said relay to disconnect the windings of the "on," "off" and "inch" relays from line L'. Such setting of the "safe" switch thus renders all control stations ineffective to start. However, such setting of the "safe" switch requires a manual operation in addition to the operation of stopping as will appear.

20 The "stop" relay 6 is normally closed (Figs. 1 and 4) and requires depression of a "stop" switch 13 for stopping at will. As shown in Fig. 5, "stop" switches 13 are connected in parallel and either is adapted to 25 be depressed to connect the winding of "stop" relay 6 across the line through upper contacts of the "reset" switches 17 which are connected in series. This energizes the "stop" relay to stop both motors as above 30 set forth and said relay has auxiliary contacts 6^a (Fig. 1) which upon response thereof parallel the "off" switches 14 as shown in Fig. 5 to effect return of the rheostat cross-heads to their initial positions. The main 35 switches 1 and 2 for the motors M and M¹ are respectively provided with auxiliary contacts 1^b and 2^b (Fig. 1) which upon opening of said switches parallel the "stop" 40 switches 13 (Fig. 5) through an up limit switch 31 of the rheostat (Fig. 1) thereby energizing the "stop" relay whenever both motors are stopped as for example by the "paper break" relay.

45 Thus the "stop" relay is energizable in a number of different ways for stopping and upon response thereof its auxiliary contacts 6^b (Fig. 1) establish a maintaining circuit therefor through the upper contacts of the "reset" switches 17 and a resistance r^a. In 50 consequence the "stop" relay also functions automatically as a safe relay requiring operation of one of the "reset" switches 17 to de-energize the same before the motors M and M¹ can be restarted either by the "on" 55 switch or the "inch" switch. In this connection it is to be understood that any number of "reset" switches may be provided there preferably being one for each control station as shown.

60 The "reset" switches 17 also have down contacts connected in parallel and each serves when depressed to connect the signal relay 11 across the line through the safe relay 8 as shown in Fig. 5 and this relay as 65 shown in Fig. 1 serves to connect across the

line an electric horn 32 or other audible signal device and one or more lamps 33 having in circuit therewith a flasher 34. Thus when either "reset" switch 17 is operated to make ready for starting it functions to give 70 both an audible and a visual signal and it may be operated at any time to give such signal even though its operation is not required for control of the stop relay. As shown the signal relay 11 has down contacts 11^a also functioning to energize the lamps 33 and to shunt the flasher 34 when the press is idle.

75 For additional protection a red light 35 (Fig. 1) is also provided, the same being 80 under the control of relay 10. This relay as shown in Fig. 4 has its winding connected across the line through the "safe" relay 8 on the one side and the "paper-break" and "stop" relays on the other side whereby it is 85 energized to complete the circuit of the red light whenever the controller is ready for starting in response to either the "on" switch or the "inch" switch.

90 What I claim as new and desire to secure by Letters Patent is:

1. In a motor controller the combination with starting and stopping means including manually operable starting and stopping switches, of means requiring manual operation of a part thereof to render said starting switch effective for restarting following operation of said stopping switch.

2. In a motor controller the combination with starting and stopping means including 100 a plurality of control stations each having starting and stopping switches, of a plurality of additional switches and circuit connections between the latter and said means necessitating operation of one of the same to 105 render said starting switches effective for restarting following operation of any one of said stopping switches.

3. In a motor controller in combination power operated starting and stopping means, 110 a control station therefor including starting, stopping and resetting elements and connections requiring operation of said resetting element as a prerequisite to use of said starting element for restarting after operation of 115 said stopping element.

4. In a motor controller in combination power operated starting and stopping means, a plurality of control stations therefor, each including starting, stopping and resetting 120 elements, and connections rendering each of said starting elements ineffective to restart after operation of one of said stopping elements until one of said resetting elements is operated.

125 5. In a motor controller, the combination with starting and stopping means including manually operable control elements to effect starting and stopping and also including an element to effect stopping automatically un- 130

- der given conditions, of means requiring manual operation of a part thereof to render said starting element effective for restarting following stopping by either of the other of 5 said elements.
6. In a printing press controller, the combination with motor starting and stopping means including manually operable control elements to effect starting and stopping at 10 will and also including an element to effect stopping automatically upon web breakage, of means requiring manual operation of a part thereof to render said starting element effective for restarting following stopping 15 by either of the other of said elements.
7. In a printing press controller, the combination with power operated starting and stopping means, of a plurality of manually operable control elements therefor, one to 20 effect starting for inching, another to effect starting for running and another to effect stopping and means requiring manual operation of an element thereof prior to restarting by either of said starting elements 25 following stopping by the other of said elements.
8. In a printing press controller, the combination with motor starting and stopping means including a plurality of manually operable control elements one to effect starting for running, another to effect stopping and another to effect both starting and stopping for inching, of means requiring manual operation of an element thereof prior to 30 restarting by either of said starting elements following stopping by the second mentioned element, said inching element being effective for stopping and restarting thereby independently of the last mentioned means.
9. In a motor controller, in combination, manually operable start, stop and reset elements and a relay responsive to said stop elements, adapted upon response to render said start element ineffective pending subsequent operation of said reset element. 35
10. In a motor controller, in combination, manually operable start, stop and reset elements, a relay responsive to said stop element and adapted upon responding to render said start element ineffective and a maintaining circuit for said relay completed thereby upon response thereof to necessitate subsequent operation of said reset element for its de-energization. 40
11. In a motor controller the combination with starting and stopping means including a stop relay, of start, stop and reset elements to control said means and connections rendering said stop relay responsive to said stop element and further rendering said start 45 element ineffective pending operation of said reset element to release said stop element. 50
12. In a motor controller the combination with starting and stopping means including a stop relay, of start, stop and reset elements to control said means and connections rendering said stop relay responsive to said stop element and further rendering said relay after response thereof, self maintaining independently of said stop and start elements 55 but subject to release by said reset element. 60
13. In a motor controller, the combination with starting and stopping means including separate relays for starting and stopping and separate control switches therefor, of additional control means for said stopping relay rendering the same effective upon each stopping operation thereof to prevent restarting pending manual operation of an element 70 of said additional control means. 75
14. In a motor controller, the combination with electro-responsive starting and stopping means including separate relays for starting and stopping, of a control statioⁿ including a plurality of switches to control said relays and circuit connections necessitating operation of a plurality of said switches to effect restarting, following stopping by said 80 stopping relay.

In witness whereof, I have hereunto subscribed my name.

THOMAS H. RODMAN.
